(57) **CLAIM**

The ornamental design for a “low profile keypad escutcheon”, as shown and described.

DESCRIPTION

FIG. 1 is a front elevational view of a low profile keypad escutcheon for an exit device in accordance with the present design.

FIG. 2 is a back elevational view of the low profile keypad escutcheon for an exit device seen in FIG. 1.

FIG. 3 is a left side elevational view of the low profile keypad escutcheon for an exit device seen in FIG. 1.

FIG. 4 is a right side elevational of the low profile keypad escutcheon for an exit device seen in FIG. 1.

FIG. 5 is a top plan view of the low profile keypad escutcheon for an exit device seen in FIG. 1; and, FIG. 6 is a bottom plan view of the low profile keypad escutcheon for an exit device seen in FIG. 1.

The broken lines are for illustrative purposes only and form no part of the claimed design.
